UNITED STATES PATENT OFFICE.

MARTIN W. LONGFELLOW, OF BALTIMORE, MARYLAND, ASSIGNOR TO THE BALTIMORE GAS APPLIANCE & MANUFACTURING COMPANY, A CORPORATION OF MARYLAND.

ATTACHMENT FOR GAS RANGES.

Application filed June 8, 1921. Serial No. 475,962.

To all whom it may concern:

Be it known that I, MARTIN W. LONGFELLOW, a citizen of the United States, residing at Baltimore, in the county of Baltimore City and State of Maryland, have invented new and useful Attachments for Gas Ranges, of which the following is a specification.

This invention is an attachment for protecting finished surfaces of gas ranges.

In that type of gas range which is provided with one or more ovens, and an open cooking space contiguous thereto, it has been found that in the course of time the walls surrounding and extending above said open cooking space, become more or less stained and discolored, thereby giving them an unsightly appearance. It is a common practice to coat the exposed surfaces of said walls with enamel, which serves a useful function because it is easily kept clean, and it also enhances the appearance of the range. Enamored surfaces, however, sooner or later exhibit discolorations which cannot be removed, due to the fact that the stains which cause them apparently enter the pores of the material to such a depth as to resist all efforts to remove them.

One of the objects of the invention is to provide simple and inexpensive means for protecting the finished exposed surfaces of the walls which lie contiguous to the open cooking space, so that the said exposed surfaces will not become stained or discolored by contact with the steam and fumes given off while the cooking space is in use. A further object is to provide a supplemental protecting wall, so mounted that it may be positioned to cover the outer face of either of two intersecting main walls, said supplemental wall having one surface to be exposed while the cooking space is in use, and another surface to be exposed when said space is not in use.

The invention will be hereinafter fully set forth and particularly pointed out in the claim.

In the accompanying drawings:—

Figure 1 is a perspective view illustrating a standard type of gas range with the invention applied thereto. Figure 2 is a detail horizontal sectional view. Figure 3 is a detail view illustrating the supplemental protector wall.

Referring to the drawing, 10 designates the base of a gas range, sustained by legs or

standards 11, and supporting the superposed broiling and baking ovens 12 and 13, and a lateral or side extension 14, the latter providing an open cooking space. In the form of range illustrated, which is of standard construction, two intersecting walls 15 and 16 are provided, contiguous to and above the open cooking space. The wall 15 serves as one end wall of the oven 13, and the wall 16 is a continuation of the back wall of the range. The features thus described are all old and form no part of the invention. The outer surface of the wall 15 may be coated with enamel, or with any other desired finish. The front surface of the wall 16 need not be provided with a high finish, such as would be desired if it were to be normally exposed to view.

The supplemental protector wall 17, consists of a plate of sheet metal, provided at one end with hinge lugs 18, which engage suitable openings 19, formed in the frame of the gas range contiguous to the intersection of the walls 15 and 16. Said supplemental wall is preferably of a size coextensive with the dimensions of the front surface of the wall 16, and is normally held in position over the front surface of the said wall 16, by means of a spring catch 20. The outer surface of the supplemental protector wall 17 is provided with the same finish as the surface of the wall 15. The inner surface of the said supplemental wall 17, is provided with the same finish as that of the front surface of the wall 16.

In practice, when the range is not in use, the supplemental protector wall 17 is in its normal position, covering the wall 16, being held in said position by the catch 20. Thus the exposed surfaces of the wall 15 and of the supplemental wall 17 are the same, and the range has the normal appearance of a standard range. When it is desired to use the open cooking space 14, the supplemental wall 17 is swung over to cover the wall 15, exposing the wall 16, and the inner surface of the supplemental wall 17. These surfaces of course are exposed to the action of the fumes and steam developed while the range is in use for cooking purposes, but may be readily cleaned in any desired manner, to remove surface accumulations. It makes no difference, however, if these surfaces are permanently stained or discolored, because when the space 14 is no longer desired for

cooking purposes, the supplemental wall 17 is swung back to its normal position over the wall 16, thereby hiding the discolored surfaces and leaving the highly finished unstained surfaces exposed to view.

The advantages of the invention will be readily apparent. It will be particularly noted that when the supplemental wall 17 is swung over to cover the wall 15, the surface 10 of said wall 15 and the highly finished surface of the wall 17 are covered, so that they are protected from contact with the fumes and steam generated while the cooking space is in use. In this manner the said highly 15 finished surfaces are protected from injury, and will maintain their original sightly condition. It will be noted also, that the supplemental wall is of a type that it may be easily applied to any standard range already in 20 use, and does not require any change in the structure of the range. An important advantage is that the supplemental protector wall may be easily removed for cleaning and scouring, and then put back in place with 25 practically no trouble.

Having thus explained the nature of the

invention and described an operative manner of constructing and using the same, although without attempting to set forth all of the forms in which it may be made, or all 30 of the forms of its use, what is claimed is:—

The combination with a gas range having a cooking space and intersecting walls contiguous thereto having exposed surfaces of different finish, of a supplemental protector 35 wall mounted to swing over said cooking space to selectively cover the outer face of either of the first mentioned walls, said protector wall having one surface provided with a finish corresponding to that of one of the first mentioned walls and the other surface of the protector wall having a finish corresponding to that of the other intersecting wall, and means for maintaining said supplemental wall in a normal position 40 covering one of said intersecting walls, whereby the exposed surface of said supplemental wall and the other intersecting wall are provided with the same finish.

In testimony whereof I have hereunto set 45 my hand.

MARTIN W. LONGFELLOW.
